UNITED STATES PATENT OFFICE.

BROR WITH, OF SKOEN, NEAR OSLO, NORWAY.

SKI TIE.

Application filed February 7, 1928, Serial No. 252,567, and in Norway February 11, 1927.

The present invention relates to ski ties of the type in which clamping members secured to the toe irons may be caused to press against the sole of the shoe and thus retain the shoe in position by pressing the same against the ski proper or against the horizontal portions of the toe irons. Preferably the said horizontal portions of the toe irons are provided with upwardly extending pegs which penetrate somewhat into the shoe sole from the underside thereof and ensures that the shoe shall not slip. The clamping members hitherto known consist of rigid levers which always occupy the same relative position to the edge portion of the shoe sole, whereby the said sole will after some time become so worn or depressed that it permits the shoe to move somewhat in the longitudinal direction of the ski, which again causes that the pegs which penetrate into the sole will enlarge the holes therein, and rigid connection between the sole and the ski tie is no longer obtainable.

It is the object of the present invention to remove the above mentioned drawbacks, and this is obtained by constructing the clamping members in form of levers which are so arranged that they exert a resilient pressure against the edge portion of the shoe sole, and adjust themselves in view of eventual wear of the shoe sole. Hereby is obtained that the shoe sole is always pressed against the ski with a pressure sufficient to prevent the shoe from sliding in the tie.

The invention is illustrated by way of example in the annexed drawing—

Fig. 1 is a longitudinal vertical section through the ski tie and a portion of the ski and

Fig. 2 is a plan view thereof.

To the ski 1 are by means of screws secured toe irons 2, 3 the horizontal portions 2 of which are provided with pegs 5.

A somewhat V-shaped bail 6 has its free ends 7 bent outwardly and is by means of said ends journalled in apertures provided in the

vertical portions 3 of the toe irons. The bail 6 is formed of a metal rod or wire of suitable thickness to have the desired yielding property, and the front end of the bail 6 may be pressed down by means of a suitable arrangement, here illustrated as a strap 8 which is passed around the bail and is secured to a clamp 9 fixed on the ski.

The portions 10 of the legs of the bail in front of the end portions 7 are curved somewhat downwardly, so that when the bail is pressed down by means of the strap 8 said portions 10 will press yieldingly against the edge portions of the shoe sole. In order to obtain a better grip between the bail and the shoe sole the portions 10 of the bail may be provided with a coating of rubber or the like as indicated at 11 in Fig. 1.

The portions of the vertical members 3 of the toe irons are above the holes therein bent outwardly so that channels or grooves 12 are formed. When the bail is swung up to inoperative position the legs of the bail pass into said grooves 12, so that the shoe is fully free to pass in between the toe irons and down on the pegs 5.

Having now particularly described and ascertained the nature of my said invention, and in what manner the same is to be performed, I declare that what I claim is:

1. A ski tie comprising toe irons having substantially vertical side portions, a resilient clamping bail pivoted to said vertical portions at the ends of the bail legs, each leg having between the pivot and the transverse portion of the bail a downwardly curved portion adapted to rest against the shoe sole, and means for pressing the clamping bail onto the edge of the shoe sole.

2. A ski tie according to claim 1 in which each of the vertical side portions of the toe irons is provided with a groove which receive a leg of the bail when the latter is in inoperative position.

BROR WITH.
